JOSIAH S. PHILLIPS, OF SAN FRANCISCO, CALIFORNIA.

Letters Patent No. 94,508, dated September 7, 1869.

IMPROVED APPARATUS FOR ASSAYING AND TESTING ORES AND METALS.

The Schedule referred to in these Letters Patent and making part of the same.

To all whom it may concern:

Be it known that I, JOSIAH S. PHILLIPS, of the city and county of San Francisco, State of California, have invented a Portable Automatic Assaying-Apparatus; and I do hereby declare the following description, and accompanying drawings, are sufficient to enable any person skilled in the art or science to which it most nearly appertains, to make and use my said invention or improvements without further invention or experiment.

My invention relates to a portable automatic assaying-apparatus, or an apparatus for ascertaining the qualities and quantities of the base and precious metals, with respect to their quantity and purity, by the use of which any person, although unacquainted with the use of the blow-pipe, can, after a short period of instruction, become sufficiently versed in its use to test, with a considerable degree of accuracy, the nature of any of the ores generally acted upon by the blow-pipe; and

It consists in the combination and arrangements of all the necessary fluxes, blow-pipes, reducing and capping-apparatus; scales and weights for weighing the ore; and, finally, the button, the product of the ore; the whole being so arranged as to be packed within a very limited space, suitable for transportation, and is intended more especially for prospectors' and millers' use. Each part is so constructed and arranged as to perform its work perfectly, and without the necessity of scientific skill in its manipulation.

In order to explain my invention, so as to enable others to fully understand its construction and operation, reference is had to the accompanying sheets of drawings, and letters marked thereon, the same letters indicating identical parts, wherever they occur, in which—

Figure 1, sheet 1, is a perspective view of the apparatus.

Figure 2, sheet 1, is a view of the cupel.

Figure 3, sheet 2, is a vertical section, showing the interior of the water-space.

Figures 4, 5, 6, 7, and 8, sheet 2, are detailed views of parts of the apparatus.

A is the base or pedestal of the apparatus, and is pierced with holes on two or more of its sides, in which are placed cups or vessels B B, for containing the various fluxes required to promote the fusion of the metals to be assayed.

C is a vessel or box, corresponding in size to the base A, the use and functions of which will be hereafter described, the two being separated a proper distance apart by a hollow vessel, D.

Upon the top of the box C is secured a metal plate, E, of smaller size than the box, which is provided

with a circular opening. This opening also passes through the box C, into the chamber inside of the vessel D.

Over the opening in the plate E is secured vertically a hollow column or cylinder, F, which may be of any desired shape, and made water-tight at its point of connection, by any suitable packing. This column is made detachable at pleasure, and serves for other purposes, to be hereafter mentioned.

When used for this purpose, the column is provided with a removable bottom, G, which has a valve, H, which lifts upward.

Inside of the vessel D is a pipe, I, which passes diagonally across the chamber, lying close to one side, as shown at fig. 3, sheet 2.

About midway of this pipe is a valve, J, which allows the air in the pipe to escape, and which, when the chamber is filled with water, is entirely submerged, but when the water is forced downward by the air introduced, and upward into the chamber F, it is gradually brought out of the water.

A rubber tube, K, provided with a mouth-piece, K', is connected with the upper end of the pipe I, the tube passing over the end of the pipe, and a metal tube, L', being forced down over the rubber, as shown in fig. 3, sheet 2, thus binding the rubber between the two tubes, and making the connection perfectly air-tight.

Upon the box C is a raised metal ridge, L, over which the rubber tube passes, and a flat spring, L', is so arranged as to bear the more easily down upon the tube, compressing and rendering the passage air-tight. This spring can be inverted, and so arranged as to be operated by the foot, the tube being free until the spring is forced down upon it.

The box C is hollow, and a portion of it filled with alcohol, oil, or other suitable fluid.

At one side of the plate E, in the box C, a slot, not shown, is cut in the top of the box, over which is placed a metal plate, N, with three or more wick-holders, a a a, projecting slightly above it.

A lever, O, is provided with holes, through which the wick-holders a a protrude, and is so arranged, that by moving it back and forth, the wicks or flames may be brought nearer to or further from the assay-cup, being also slightly elevated and depressed, as they are moved backward or forward, in order to produce the correct positions for producing the reducing or oxidizing-flames, as desired.

Communicating with the chamber in the vessel D are three or more tuyeres or nozzles, P P P, one over each wick-tube.

A conical cup, X, fig. 7, is placed inside the chamber D, fitting snugly around the opening in the plate E.

Near the bottom of this cup is a small opening, surrounded on the outside by a cap, X' , open at the top, forming, as it were, an inverted siphon, for preventing the air from escaping into the cup.

The chamber D is first filled partially full of water, and air is introduced through the rubber tube K , which causes the water to rise in the cup, and pass up, through the valve H , into the column F . The introduction of air through the tube K now being discontinued, the water in the column flows back into the cup X , through the small restricting or governing-hole a' in the bottom of the cylinder, thus compressing the air, and forcing it out more equally through the tuyeres $P P P$, upon the flames, the combination forming a very effective blow-pipe, for very large comparative quantities of ore.

The assay-cup Q is provided with a long stem, Q' , the lower end of which is formed into a screw. On the base or pedestal A is attached one end of two corresponding arms R , so that they may move freely.

Attached to the outer end of one of these arms is a circular metal plate, S , having a projection on one side, to which the arm R is attached, so that it also can turn freely in any direction.

A circular opening is cut from the centre of the plate S , in which a set of gimbals, T , or other equivalent joint, is placed.

Around the outside of the opening in the plate is a flange, around which a ring, attached to the outer end of the opposite arm R , is placed.

The lower end of the stem of the assay-cup is screwed into the inner ring of the gimbals, thus allowing it to be manipulated by the hand, so as to throw the cup at any angle or elevation required to bring the button under the action of the flames.

The cup itself is placed inside of rings U , which form a circular moving joint, the rings being attached to two springs V , which are held in place by two set-screws W , at the corners of the plate E .

The springs V allow the cup to be drawn down by the screw in the gimbals to any required position, while the joint U allows it to be inclined or shifted to or from the flame, as desired.

Y is a cork, or other non-conductor of heat, placed around the stem Q' , which the operator grasps in manipulating the cup.

Z is a metal or other band, formed so as to embrace the column F , the two ends being extended parallel to each other, to any required distance.

Between these two extended ends, and directly over the assay-cup, are pivoted two or more curved fingers, $b b$, which may be folded up between the two ends, for transportation, when they will assume the position indicated by the dotted line.

These fingers, when extended, are separated, and a lump of charcoal, d , is suspended between them, directly over the assay-cup. This charcoal is only used when a reducing-heat is required; and when it has caught on fire, and the air from the nozzles plays upon it, it will be kept in a continual glow, aiding the reduction of the metal to a great degree. When the oxidizing-flame is used, the charcoal is removed, and a piece of soapstone, or other non-conducting, fire-resisting, and non-reducing substance is substituted in its place, for cupellation of the precious metals.

A portion of the box C , shown at fig. 1, sheet 1, with raised lid e , is occupied by a weighing-device, by which the ore first, and finally the button, the product of the ore, is weighed.

The scale shown at fig. 4, sheet 2, represents more clearly the operation of my scale.

f represents a long scoop-shaped lever, resting upon bearings at g , upon the long end of which the button is placed, and the ore-sample is weighed on the short end in the pan. The bearings or trunnions on which

the beam f rests are sharp at the bearing-point, so that but very little friction is induced by the turning of the beam.

A weight, h , is suspended from the short end of the lever, which counterbalances the weight of the button. Four or more of these weights may be used, in accordance with the number of scales of figures employed, and one for weighing the ore-sample.

The scale is represented at fig. 5, sheet 2, and may be made up of any number of columns of figures, placed at the proper distances apart, to correspond to the increasing length of lever. These scales are marked with numbers, which represent the number of dollars per ton the ore from which the button is obtained will yield, the calculation being made on the scale with reference to the button, each row of figures representing the value for a stated amount of ore, and each weight being employed to represent that amount, in their respective columns, and the ore-weight for the sample being placed over the last line, or forty dollars, (\$40,) for weighing the sample.

For millmen and prospectors, it is very desirable to ascertain with greater facility whether or not there is sufficient silver or other metals to pay the cost of mining and extraction, and, in order to obtain the approximate value, I have devised, in addition to the scales already described, a flat plate, p , perforated with one or more holes, r , of different and suitable sizes, countersunk on the upper side, into which the globule from the assay is dropped, so as to measure the button, in order to obtain its value in dollars per ton, the smallest representing forty dollars (\$40) per ton for silver, or the least quantity that can be worked profitably, and if it does not pass through the smaller hole, it is of greater value.

For more readily obtaining the value per ton the ore will yield, and more especially when the button is of a small size, for gold and silver I use two metal strips, r , secured on any level surface, y . These strips gradually diverge from a common point, similar to the lines used in Harkort's scale for the same purpose. The ounces or money-value is marked on these strips, one side for silver and the other side for gold, opposite the width which will receive a button of the value marked. This mode of obtaining the value of the button renders the Harkort theoretical principle prompt, practicable, and reliable for the unskilful millman or prospector.

Sometimes, in operating the ores, it will be inconvenient for some operators to employ their breath for furnishing air for the blast. To meet this emergency I have attached to the apparatus a small bellows, i , which is arranged to be operated by the foot, the mouth-piece K on the tube K being inserted into the induction-opening k , and receiving the air from the bellows, conveys it into the chamber D . The induction-valve j is, as shown in fig. 6, sheet 2, at the bottom of the bellows, the air being both received into and discharged from the bellows at the bottom, through the bed-plate upon which the bellows rests by a check-valve and an inverted siphon-tube and valve, j' . The column F is to be a cylinder, or any other suitable form, and serves for containing the water which gives the pressure, pedestal for roasting, drying, evaporating, or filtering, as well as for holding the covering charcoal and non-conducting, fire-resisting, and non-reducing material for smelting and cupelling. It also serves to suspend the assaying-furnace and cupelling-muffle in more elaborate and generally-varied assays, and by covering the upper end with a sieve, m , it serves for sifting the pulverized ore, and forms a receptacle for a portion of the tools in travelling.

For cupelling, I use a cylindrical metal tube, n , open at both ends. The interior of this tube is filled with bone-ash, made concave at the ends, so that after the

button has been refined to a certain extent, upon one end of the tube, it can be transferred to the opposite end, where the refining is completed. The ends of this cup are provided with four recesses, q' , made at the four quarters of the periphery of the cup, extending downward to the upper rim of the concave bone-ash, so that one centre flame may oxidize, and the two side flames keep the metal and ash hot. The bone-ash can be used alone when made of the form above described, without the outside metal tube or cylinder.

The assay-cup, covering of suspended charcoal, and system of levers and joints for manipulating the same, above described, can be used with equal facility, with the common blow-pipe, for producing the blast, and at a great advantage over the method usually employed.

The operation of producing an assay by the use of my apparatus is as follows:

I first crush the ore to be assayed to the proper degree of fineness, after which it is thoroughly mixed and sized by means of the sieve m , placed on the end of the column F . By the ordinary blow-pipe treatment, one grain is the amount of ore treated at a time, but by the use of my apparatus, fifteen and one-half grains, troy, can be operated upon at once. After sizing, fifteen and one-half grains, or ten decigrammes of the ore is weighed out upon the scales at the back of the apparatus, and mixed with test-lead and suitable fluxes from the boxes B B , and placed in a cylindrical soda-paper box. This box is then placed in a cavity, in a piece of charcoal or other moulded combustible material, which fits into the assaying-cup Q . Water is then placed in the chamber D , to about three-quarters of its capacity, and air introduced through the elastic tube K , thus forcing the water through the inverted siphon into the vertical cylinder F . The air, being compressed by the column of water, is forced out through the three tuyeres P P P , thus driving or concentrating the flames upon and around the cup containing the assay.

The centre flame plays directly upon the front of the assay, while the two outside flames play upon the sides or rim of the charcoal, first with the oxidizing-flame until the assay is sufficiently fused with the fluxes to prevent loss, and then with the full reducing-flame, for a period of from ten to twenty minutes, until the scoria or slag becomes orbicular, during which period the assay is kept in suitable positions by shifting the assay-cup, by means of the levers and universal joints, and the elevating and depressing-screw and springs on the assay-holder.

During the operation of assaying, a piece of charcoal or other moulded combustible is kept suspended by means of the charcoal-holder Z .

The cupellation is performed in the tube u , substituting it in place of the reducing-cup, and the flame from the centre tuyere is blown directly through one of the recesses in the tube upon the lead button of the assay, and at the same time the two side flames are directed under the outer rim of the cup on either side of the recess, warming the cup and keeping it at an equal maximum heat. The tube is turned when necessary, so as to allow the centre flame to play through either of the recesses, the oxidizing-flame being used. During this operation the assay is covered by the soapstone or other suitable material employed in its stead. After a sufficient length of time has elapsed, and the silver button is obtained, it is weighed upon the scales at the rear of the apparatus, to ascertain the value, per ton, of the ore from which the assay was taken, which is, after balancing with one of the weights, read at sight from the scale.

For roasting and assaying tin, copper, lead, or other minerals, I use a cylindrical furnace, t , filled with charcoal or other reducing-mixture, and place it in front of the flames and nozzles. The furnace and char-

coal are pierced with holes or openings in such positions as to admit the flames into the body of the charcoal, in which is placed a crucible for blow-pipe, or crucible-assaying of these minerals, which also forms a transverse muffle for cupelling silver and gold buttons with bone-ash cupels.

By the use of this apparatus I am enabled to make perfectly accurate and reliable assays of ore in any required quantities, reducing the operation to a mechanical process, easily acquired by persons not familiar with mineralogy or assaying. The apparatus, when packed ready for transportation, and containing all the necessary furniture and articles for producing an assay, will not occupy more space than a cube of from five to seven inches, nor weigh more than eight pounds, making it invaluable for the prospector and others who cannot at all times find a practical assayer, in order to test their ores.

Having thus described my invention,

What I claim as new, and desire to secure by Letters Patent, is—

1. The stand, consisting of the pedestal A , hollow connecting-vessel D , box C , and plate E , substantially as above described.
2. The boxes B B , secured in the pedestal A , for the purpose of containing the various fluxes required during the assay, substantially as herein described.
3. The diagonal pipe I , with its valve J , in combination with the tube K , for introducing air into the water in the chamber D , substantially as and for the purpose above described.
4. The flat spring L' , in combination with the pointed ridge L , for compressing the tube, and preventing the return of the air or water, substantially as herein set forth.
5. The conical cup X , with its inverted siphon X' , when placed in the chamber D , substantially as and for the purpose herein set forth.
6. The column or cylinder F , when used either with the bottom G , with its upward-lifting valve H , as a receiver of the water when it is forced upward by the air introduced in the chamber, and the small hole a' , for permitting it to flow back more equally to produce a pressure, or when used in combination with the sieve m , for mixing and sizing the pulverized ore, substantially as herein set forth.
7. The metal plate N , with its three or more upward-projecting wick-holders a a , said plate being movable by means of a lever, O , by which the wicks are shifted so as to produce a reducing or oxidizing-flame at pleasure, substantially as herein described.
8. The three or more tuyeres or nozzles P P P , communicating with the interior of the chamber D , and through which the air is forced against the flames for the purpose of propelling them against and upon the assay, substantially as described.
9. The assaying-cup Q , with its long stem Q' , the lower end of said stem being formed into a screw, substantially as and for the purpose herein described.
10. The upper and lower sets of universal joints, consisting of the arms R , circular plate S , gimbals T , or other equivalent joint-rings U , and elevating and depressing-springs V , the whole constructed and arranged substantially as and for the purpose herein described.
11. The fingers b b , attached to the end of the band Z , for suspending a piece or pieces of charcoal or other required material, above the assay, substantially as and for the purpose herein described.
12. Suspending a piece or pieces of charcoal, d , above the assay for the purpose of intensifying and equalizing the heat on the assay, substantially as described.
13. The weighing-device, consisting of the long scoop-shaped lever f , balanced by means of weights, upon sharp bearings, for the purpose of weighing the

ore, and the button after the assay, substantially as set forth.

14. In combination with the beam *f* of a weighing-device, a scale or series of scales, each scale corresponding with weights *h*, whereby the number of dollars per ton, the ore from which the button was taken will yield, can be read from the scale by merely balancing the button on the beam, substantially as herein described.

15. In combination with the apparatus hereinbefore claimed, for producing a blast, the bellows *i*, operated either by the foot or hand, substantially as and for the purpose herein described.

16. The cupelling-tube *n*, with its recessed rims, said tube being filled with bone-ash concave at both ends, substantially as and for the purpose described.

17. The metal plate *p*, having the graduated holes

r, each hole being marked to represent the ounces or money-value, per ton, the ore will yield, said value being found by passing the button through the hole, substantially as described.

18. The diverging strips of metal *v*, placed on a bed-plate, *y*, and graduated to the dollar or ounce-value per ton, or other coin-value, substantially as herein described.

19. A portable automatic assaying-apparatus, constructed and arranged to fold within the space herein specified.

In witness whereof, I have hereunto set my hand and seal.

J. S. PHILLIPS. [L. S.]
